UNITED STATES PATENT OFFICE.

WILLIAM J. YOUNG, OF CLEVELAND, OHIO, ASSIGNOR OF ONE-HALF TO
FRED W. BEAU DE ZART.

LIQUID-CARBONATING APPARATUS.

SPECIFICATION forming part of Letters Patent No. 761,434, dated May 31, 1904.

Application filed April 25, 1902. Serial No. 104,589. (No model.)

To all whom it may concern:

Be it known that I, WILLIAM J. YOUNG, a citizen of the United States of America, and a resident of Cleveland, in the county of Cuyahoga and State of Ohio, have invented certain new and useful Improvements in Liquid-Carbonating Apparatus, of which the following is a specification.

My invention relates to improvements in liquid-carbonating apparatuses; and the object of my improvement is to provide a simple inexpensive contrivance which is of compact construction and extremely simple in point of operation and manipulation. I attain this object in an apparatus constructed substantially as shown in the accompanying drawings, in which—

Figure 1 represents an exterior and part sectional view of said apparatus. Fig. 2 is an end elevation of the same. Fig. 3 illustrates partially an enlarged central sectional view of said apparatus; and Fig. 4 is a horizontal sectional view of a part thereof on line X X, see Fig. 3.

Like letters of reference denote like parts in the drawings and specification.

Substantially this apparatus comprises a plurality of cylinders A A A and a tank B, of which the former are secured upon and arranged in open relation with the latter. In the cylinders carbonating of the liquid is effected, which liquid accumulates within the tank B. Comparatively such apparatus is of a low structure and can thus be placed under counters in stores, &c. Projecting from each of the cylinder-heads a is a cage a', all of which are connected by the pipe-line c, which also contains a check-valve d. Through said pipe c liquid is supplied to all of the cylinders. The liquid-pressure is in excess over the gas-pressure, and gas enters the tank B by way of pipe e.

Arranged in adjustable connection with each of the cover-cages is a spherically-shaped deflector e', whereby the liquid can be delivered into the cylinders in thin circular sheet-like form. Within each of the cylinders is placed a secondary cylinder D, having a central tube f extending therethrough. (See Figs. 3 and

4.) Connected with either the outer shell g or the tube f, or both, are a series of wings or spiders h. Simply to facilitate building up of said spiders I prefer to construct the cylinders in halves, as indicated in Fig. 4. The liquid in passing down through the cylinders encounters successively a plurality of obstructions, which divide the liquid many times over and over again ere it can reach the tank A.

As shown, the spiders h extend radially from the tube f to the shell g, leaving ample space between them for the liquid to fall onto the wings i, which project from the tube. Thence the wings j are met, which extend inwardly from the shell g. Next below are another series of spiders, and so on. The wings and spiders overlap one another, and with such arrangement it is impossible for the liquid to reach the tank A in a straight downward course.

As above stated, the gas enters the tank by way of pipe e, from where it ascends through tube f, as well as between the spiders and wings. Thus at all times the gas can rise freely to commingle with the inflowing liquid. Carbonating of the liquid can therefore be effected to the maximum extent. The check-valve e' guards against a return flow of the liquid into the gas-pipe, while the normal flow of the gas will automatically open said valve and maintain it in open condition.

The screw-threaded connection of the deflector-stems with the cages a' admits of accurate adjustment of said deflectors, so that at all times an equal amount of liquid may flow past any of said deflectors. Should the pressure within the cylinders and tank attempt to exceed a predetermined status, then the check-valve d will automatically close and shut off the supply of liquid for all the cylinders, it being presupposed that the liquid-supply pump (not shown) is so set as to continue operation against a certain pressure only. The carbonated liquid is drawn off through pipe h, which pipe is extended to any convenient point, as location and application may dictate.

What I claim, and desire to secure by Letters Patent, is—

1. A carbonating apparatus comprising a

plurality of mixing-cylinders, a storage-tank for the mixed liquid arranged underneath and in open relation with all of said cylinders, interior cylinders containing a series of alternately - arranged overlapping spiders and wings, and a central tube, said spiders and wings causing diffusion of the liquid, and the said tube establishing an auxiliary passage for the gas, a liquid-supply pipe communicating with the heads of all of the first-named cylinders, a gas-supply pipe, a check-valve intersecting said pipes to allow the flow of liquid and gas in normal direction only, a liquid-discharge pipe extending from the lower portion of said tank and deflectors having adjustable connection with and within the heads of said cylinders to enable regulation of the flow of liquid into each of said cylinders.

2. In a liquid-carbonating apparatus, an auxiliary cylinder within a carbonating-cylinder, the said auxiliary cylinder comprising a shell, an internal tube, a series of spiders ar-

ranged between said shell and tube, and a series of wings located between said spiders which project alternately from said shell and the said tube whereby continual interruption of the flow of liquid is caused for purpose of enhancing absorption of gas by said liquid. 25

3. In a liquid-carbonating apparatus, a plurality of upright cylinders, a horizontal tank 30 extending underneath said cylinders, a gas-supply and liquid-drain pipe connected with said tank, a liquid-supply pipe provided with a check-valve, and communicating with the heads of all of said cylinders and atomizing 35 devices within said cylinders, all substantially as and for the purpose set forth.

Signed at Cleveland, Ohio, this 28th day of August, 1901.

WILLIAM J. YOUNG.
